UNITED STATES PATENT OFFICE.

OSCAR H. HALSTEAD, OF MANHATTAN, KANSAS.

ADDING MACHINE.

Application filed September 9, 1918. Serial No. 253,248.

To all whom it may concern:

Be it known that I, OSCAR H. HALSTEAD, a citizen of the United States, residing at Manhattan, in the county of Riley and State 5 of Kansas, have invented certain new and useful Improvements in Adding Machines, of which the following is a specification, reference being had therein to the accompanying drawing.

- 10 My invention relates to improvements in adding machines, the objects of which are, first: to provide a simple, substantial, durable and efficient machine of this class, in the operation of which, practically all of the 15 functions of a high grade adding machine are performed by the minimum number of parts, thereby greatly reducing the cost of manufacture, second: to so construct and arrange the parts of an adding machine, that 20 the totals indicated and the items printed thereby, shall at all times be visible to the operator, at a single glance, and that the machine shall be set for performing its various functions, by the minimum number of 25 keys, third: to so construct the key board mechanism that but one key of any one denomination can be set at one time, fourth: to so arrange the parts of an adding machine, that when the items and totals are set 30 to what is termed clear, the same is visibly indicated in the machine and may be printed without extra movement of the operating lever, and without the use of any extra printing character and parts connected with the 35 latter, thereby reducing the number of manipulations and the number of parts in the machine, fifth: to provide extremely simple and substantial means by which the machine may be set for multiplying.
- 40 I attain these objects by the mechanism illustrated in the accompanying drawing, in which: Fig. 1 is a side view of the machine embodying the mechanism, certain parts being broken away. Fig. 2 is a top plan of the 45 machine. Fig. 3 is a bottom plan of the actuating mechanism. Fig. 4 is a side view of the ribbon moving mechanism. Fig. 5 is a side view of the calculating mechanism, showing the parts in position for printing 50 a cipher. Figs. 6, 7 and 8 are enlarged side views in detail, showing the calculating mechanism in different positions, certain parts being omitted and other parts being broken away. Fig. 9 is an enlarged view in 55 detail of a number of the carrying segments and their carrying pawls, looking toward
- the left. Fig. 10 is an enlarged section in detail of the calculating mechanism, cut transversely on the line XX, seen in Fig. 11, looking toward the right. Fig. 11 is an enlarged side view in detail of the totaling mechanism, showing the calculating mechanism in another position, certain parts being omitted and others broken away. Fig. 12 is an enlarged view in detail of the totaling and the clearing mechanisms, in position for printing a total, looking toward the left. Fig. 13 is an enlarged section in detail, cut vertically through the center of a number of the rack holding bars, looking toward the right. Fig. 14 is an enlarged top plan, in detail of the holding and cipher bar clearing mechanism. Fig. 15 is an enlarged section in detail cut transversely through a portion of the key clearing bars, on the line YY, seen in Fig. 14, looking upward. Fig. 16 is an extra enlarged side view in detail of a part of the printing type, looking toward the left, certain parts of the type carrier being broken away. Fig. 17 is a side view of the lower end portion of the operating lever with its connected parts at the extremity of their movement toward the right.
- Referring to Figs. 1 and 10, wheel shaft 1, has its ends rigidly secured in frame sides 2, 85 and has a plurality of sleeves 3 rotatably and slidably mounted thereon. Each one of said sleeves has a pawl carrier 4 oscillatably mounted thereon and a total wheel 5, a cam 5' and a disengaging cone 6 formed integrally therewith. Said cam has the cam faces 5" and 5'a formed on the surface as seen in Figs. 6 and 11. Each sleeve has a drive wheel 7 rotatably mounted thereon, adjacent to said total wheel: and since each one of 90 said drive wheels with its adjacent total wheel and pawl carrier and their hereinafter described parts, form one of a plurality of calculating mechanisms, which are alike in construction and operation: but one of said 95 mechanisms is described in detail. Drive wheel 7 has a stop arm 8 formed integrally therewith, and lift pinion 9, drive gear 10 and collar 11 rigidly secured thereon. Drive wheel 7 has a drive pawl 12 oscillatably 100 mounted on its inner surface. Said pawl has pawl lever 12' formed therewith. Said pawl is engaged with the ratchet teeth 13, which are formed on the inner surface of indicator drum 14, which latter has total indicator character 14' on the periphery, formed with total wheel 5. Said drum has stop stud 105
- 110

15 secured in its face; said stud being adapted to be moved into the path of travel of drive wheel stop arm 8. Total wheel 5 has the concaved faces 17 formed on its peripheral surface, against which the holding wheel 17' is yieldably held, for yieldably holding said total wheel against rotation. Drum 14 has notches 18 formed in its peripheral surface, which are engaged by the hereinafter 10 described carrying pawl. The undesignated one of the shifter arms 3" (see Fig. 12) is pivotally connected with the lower end of the L crank 3^a, the upper end of which is pivotally connected with the lower end of 15 the shifter rod 95", which latter forms part of the hereinafter described totaling mechanism. Referring to Fig. 1, drive gear 10 is engaged with the slidably mounted gear rack 19, which latter has bracket 20 formed therewith. Said bracket has holding shoulder 21 and stop shoulder 22 formed on its under edge. Said rack is also provided with stop shoulders 23 and 24 formed on the upper surface of its extended portion 25. Said holding shoulder detachably holds said rack against its hereinafter described longitudinal movement: while said stop shoulders are adapted to stop said rack at various points, when abutted against the hereinafter 20 described parts. Said extension 25 has rack stop stud 26 secured in one side thereof which stud is adapted to be moved against rack bearing 27, for limiting movement of said rack in one direction. Said rack has the 25 segment actuating stud 28 secured in its upper right corner for actuating gear segment 29 upon the return movement of said rack. Holding bar 30 is mounted for slidable movement through apertures formed through upper guide plate 31 and lower guide plate 32. The ends of said upper guide plate are secured on the inner surfaces of frame sides 2, as seen in Fig. 13, while said lower guide plate has its front edge secured on the inner 30 surface of the front piece of the frame of the machine, as seen in Fig. 1. The rear end of said lower guide plate is secured on guide supporting bar 32', which bar also acts as a stop for stopping recover movement of racks 35 19, as hereinafter described.

Referring to Fig. 13, since all of the plurality of holding bars 30 are alike in construction and operation, a detailed description of one of said bars is deemed sufficient. Guide plate 31 has a vacant aperture formed therethrough at units place 1^a and no holding bar at said place; the upper portion of a bar 30 is slidably mounted in said plate at tens place 10^a, hundreds place 100^a, and so on 40 including the highest denomination of place within the scope of the machine, which may contain mechanisms for any desired number of places. Since all of the holding bars 30 are alike in construction and operation, a 45 detailed description of but one is deemed

sufficient. Said holding bar has actuating flange 30' formed on its upper end portion and is provided with spring 30" between said flange and guide plate 31 for yieldably moving said bar upward. Said bar has the 50 overlap flange 33 and the underlap flange 34 formed therewith. The overlap flanges of said plurality of bars overlap the underlap flanges of the adjacent bars of lower denominations respectively. This provides bar 55 moving means, whereby the downward movement of a bar of higher denomination, moves downward, all of the bars of lower denomination, for purposes hereinafter described.

Referring to Fig. 1, the key stems 1', 2', 3', 4' and 5' have their upper ends slidably and oscillatably mounted in apertures 35' formed through keyboard 35, and their lower ends similarly mounted in lower guide plate 32. The lower ends of said key stems have studs 38 secured therein. Said studs are adapted to be moved into the path of travel of shoulder 23 of rack extension 25, for stopping rack 19 at five points of its travel toward the 60 right, which points correlate with the hereinafter described printing mechanism. Key stems 6', 7', 8', and 9' are similarly mounted and their studs in like manner, act in conjunction with shoulder 24 for stopping rack 19 at four other points of its travel toward the right. Since said key stems are otherwise alike in their construction and operation, a detailed description of but one key stem is deemed sufficient.

Referring to Figs. 1 and 14. Stem 1' has a ratchet tooth 36 formed on one edge of its upper end portion, a depressing stud 37 secured therein below said tooth, and a holding stud 38 secured in the lower end thereof. Said holding stud is moved into contact with the under surface of guide plate 32, for limiting upward movement of said stem. Said stem is provided with button 1" secured on its upper end, and is manually 105 moved downward, by pressure upon said button until its stud 38 is stopped against the upper surface of rack extension 25, with tooth 36 below the level of keyboard 35. Spring 39 has its lower end secured to stem 100 1", and its upper end secured in an eye 39' formed on the lower surface of bearing plate 40, which plate extends beneath the entire keyboard and is secured to the end piece and side pieces 2 of the frame of the machine as seen in Fig. 1. Said spring is adapted to move said key stem upward and laterally, for bringing tooth 36 into engagement with the under surface of key board 35, and for similarly moving said stem when said tooth is released from said engagement, as hereinafter described. Said key stem passes through a loose fitting aperture formed through key clearing bar 41, which is slidably mounted between said bearing 115 130

plate and key board. The depressing stud 37 extends across the top surface of depressing shaft 42, which shaft is oscillatably mounted on the under surface of bearing plate 40. A cipher bar 43 for each one of the denominational places of the machine is mounted in the same manner as the previously described holding bar 30. Since all of said cipher bars are alike in construction and operation, but one is described. Said cipher bar has a flange 43' formed on its upper end portion, which flange projects beneath shaft 42. Said bar is provided with spring 43'', between said flange and guide plate 31, for yieldably moving said cipher bar upward. The upper ends of bars 43 and 30 are stopped against the under surface of bearing plate 40, for limiting their upward movement. It will readily be understood from the foregoing description, that depression of any one of the key stems 9'', moves its depressing flange downward, thereby depressing the shaft 42, which in turn downwardly moves the bars 30 and 43 which are in the same denominational place as said key. It will also be understood that where said depressed key stem 9'' is of a higher denomination, that the flanges 33 and 34 of the cipher bars 30, downwardly move all of the cipher bars of a lower denomination. Since stems 1'' to 9'', inclusive, may be termed digit key stems, for brevity hereafter, the described parts will be termed digit actuated bar clearing means.

Referring to Figs. 1 and 15. Each one of the denominations of key stems 1' to 9', inclusive, is provided with one of the previously mentioned key clearing bars 41, and since said bars are alike in their construction and operation, but one is described. Bar 41 is independently moved toward the right, by the lateral movement of any one of said key stems, when said stem is manually moved downward, and is moved toward the left, by the previously described spring actuated movement of said depressed stem. It will be understood, that should a second one of said key stems be pushed downward, that said second stem would so move said release bar, that the first depressed stem would thereby be released and return to normal position. This mechanism will, for brevity be termed individual key releasing means. Bar 41 has the upturned end portion 41', formed thereon, which portion is adapted to be moved toward the right, by oscillation of the oscillatably mounted clearing shaft 44. Said shaft is automatically moved toward the right, by the hereinafter described mechanism, for moving a plurality of said bars, which for brevity I shall hereafter term, simultaneous key releasing means. Said shaft has one end of pull rod 45 connected therewith. The other end of said pull rod is slidably mounted in bearing 46, which is formed with one of the frame sides 2. The last mentioned end of said pull rod is provided with the collar 47, which is secured thereon. Collar 47' is slidably mounted on said rod with spring 48 mounted on said rod between said collars, for forming anticoncussion means for said rod. Arm 49 is secured on one end portion of sleeve 50, which is oscillatably mounted on shaft 51, the ends of which are similarly mounted in frame sides 2. The upper end of said arm is adapted, during the end portion of its return stroke, to strike against and move said anticoncussion means, and thereby move all of said clearing bars toward the right, for simultaneously clearing all of said key stems that may have been set. The operating lever 52 has its lower end secured on one end of said sleeve, while its upper end is provided with handle 52' seen best in Fig. 1. An arm 53 is secured on end of sleeve 50, the free end of which has the actuating lug 53' formed thereon, which overlaps one edge of arm 54, for moving the last mentioned arm toward the right, as seen in Figs. 1 and 3. Spring holding stud 53'' is formed on the lower end portion of lever 53. One end of spring 55 is mounted on said stud, while the other end of said spring is mounted on a corresponding stud 54' which is formed on the adjacent edge of arm 54. This spring and its connected parts form yieldable stopping means whereby lever 52 and its connected parts are yieldably stopped at the end of their return stroke, as, and for purposes hereinafter described. A companion arm 54a, (see Fig. 3) is secured on the other end of sleeve 50. The ends of rod 56 are secured in the free ends of arms 54 and 54a. One end of pull spring 57 is connected with said rod (see also Fig. 1) while the opposite end of said spring is connected with the extremity of extension 25, of gear rack 19, whereby said rack is pulled toward the right. Each end of rod 56 is provided with a recover spring 58, one end of which is connected therewith, while the other ends of said springs are connected with the front piece of the frame of the machine, for pulling said rod toward the left. Said rod has a friction roll 59, rotatably mounted thereon, which is yieldably held in contact with rack lug 19', for moving said rack throughout its recover movement. All of the racks 19 are similarly provided with recover moving means. Ratchet segment 60 is secured on the lower end of the arm 54, and has trip lugs 60' and 60'' formed respectively on its end portions. Pawl 61 is oscillatably mounted on one of the frame sides 2 and engages said ratchet segment for preventing return movement of said arm, until the same has almost reached the end of its movement toward the right. Said pawl has trip lever 61' formed therewith,

the free end of which is adapted to be moved by said lugs for oscillating said pawl from the position seen in Figure 1, to the position seen in Figure 17, and vice versa. 5 Said pawl is provided with spring 61", which is adapted to yieldably hold said pawl in said positions. Said ratchet segment and the therewith operatively connected parts, form an arm holding means, whereby arm 54 10 is held against return movement throughout the greater part of its movement toward the right.

Referring to Figs. 1, 6, 7 and 8, pawl carrier 4, has arms 4' and 4" formed therewith. 15 Gear segment 62 is one of a plurality of segments which are alike in construction and operation, of which but one is described in detail. Said segment is oscillatably mounted on arm 4" and is moved from its inner 20 position seen in Figs. 1 and 6 to its intermediate position seen in Fig. 7 by rotation thereagainst, of cam portion 5" of cam 5, which is done when cam 5 has been rotated nine steps. Said segment is moved from 25 said intermediate position, to its outer position seen in Fig. 8 by rotation therewith of cam portion 5", for moving said segment into engagement with drive segment 29, after cam 5' has been rotated through the 30 first half of its tenth step. The lower end portion of said segment has stud 63 secured therein and is provided with the latch actuating spring 64, (see Figs. 1 and 8) one end of which is connected with latch 65, while 35 its other end is connected with the lower end of segment 62. Said latch is oscillatably mounted on the end of carrier arm 4', and has latch shoulders 65', formed thereon, for holding said stud and the therewith connected gear segment in its inner, intermediate 40 and outer positions, respectively. The upper end portion of said segment 62 (see Fig. 9) has the underlap and overlap flanges 62' and 62" projecting from opposite sides thereof 45 and, respectively, formed therewith. The designated underlap flange 62' is adapted to lift the adjacent overlap flange 62" of the adjacent gear segment 62 when the last mentioned segment and its connected overlap 50 flange are in their intermediate position, shown in Fig. 7. A pawl 66 is oscillatably mounted on the end of the pawl carrier 4 of each gear segment 62 and engages the notches 18, in the total wheel 5, of the next 55 higher denomination, as seen in Figs. 6 and 9.

Referring to Figs. 1 and 6, type bar 67 is slidably mounted in slots formed in the rigidly supported bars 68 and 69, and passing 60 between drive gear 10 and collar 11 holds said gear against lateral movement, as seen in Fig. 10. Said bar has gear teeth 67' formed on a portion of one of its edges, which teeth are in engagement with lift pinion 9. Said type bar has stud 70 secured

in its upper end portion and a type carrier 72 formed on its upper end. Said type carrier carries a plurality of type 71, mounted for slidable movement therein, as seen in Figs. 1 and 16. Each one of said type is 70 provided with a spring 71', which is adapted to move said type from the rotatably mounted platen 73, which latter is of roller formation. Each one of said type carriers is provided with an oscillatably mounted hammer 74, and since said hammers are alike in construction and operation, but one is described. Said hammer is secured on the upper end of spring 74', the lower end of which is secured on the upper end of the 80 oscillatably mounted hammer bar 74". Referring to Figs. 1 and 7, hammer pull-piece 75 is oscillatably mounted on the lower end of hammer bar 74", and has stop pin 75' secured in one corner thereof. One end of 85 said pin extends past one edge of said hammer bar, for limiting oscillation of said pull-piece in one direction. The other end of said pin extends beneath one end of the oscillatably mounted pull-piece holder 76, which has weight 76' formed on its other end. One end of hammer spring 77 is connected with the upper corner of said pull-piece while the other end of said spring is connected with the fixedly mounted rod 78, 90 for pulling said pull-piece and the therewith connected lower end portion of hammer bar 74". The intermediate portion of pull-piece holder 76 passes beneath pin 70, by which said holder is held in its normal position, 95 until said holder is released by upward movement of type bar 67 and the thereby carried pin 70. The lower corner of said pull-piece is held by holder 76 out of active position, as seen in Fig. 1, with relation to 100 the rotatably mounted cam 79, and is oscillated from said position into active position seen in Figs. 6 and 7, by spring 77. The upper end of hammer bar 74" is stopped against hammer stop 80, which limits the 105 movement of the same, toward type 71. Cam 79 is crank and rod connected with the end of the oscillatably mounted L crank 81 (Fig. 1), by crank 79' and rod 79". The lower end of said L crank has lug 81' formed 110 thereon. Said lug is moved toward the right by movement thereagainst of arm 54", (see Fig. 3), for actuating the previously described printing mechanism during the last portion of the movement of said arm toward 115 the right as seen in Fig. 17. Referring to Figs. 1 and 2, platen 73 is secured on the rotatably mounted platen shaft 73', which latter has platen ratchet wheel 73" secured on one end portion thereof. Pawl 82 is 120 oscillatably mounted in the upper end of rocker arm 83. Said pawl engages said ratchet wheel for rotating said platen, and thereby feeding paper 84 from paper reel 84'. Said paper passes from said reel be- 125 130

tween said platen and the rotatably mounted 5 guide roller 85, the surface of which is preferably formed of elastic material. Ribbon guide 86 is oscillatably mounted on platen shaft 73'. Said ribbon guide has shoulder 86' formed thereon, which shoulder is oscillated by movement thereagainst, of the upper end of rocker arm 83, for slightly lifting ribbon 86^a. The lower end of said 10 rocker arm is actuated by movement thereagainst of cam 87 (see also Fig. 3) which is secured on one end of sleeve 50. Said cam is of such form, that it moves the lower end of said rocker arm toward the right, during the 15 first part of its counter clock wise rotation and holds said arm in its thus moved position, seen in Fig. 1, during the latter part of said movement. Ribbon 86^a (see Figs. 1, 2 and 4) is what is known as a bichrome ribbon and has its upper half 86^b formed for printing a certain color on paper 84 while the lower edge portion 86^c similarly prints a different color. Said ribbon is wound on ribbon reels 88 (see also Fig. 2) which reels 20 are slidably splined on ribbon reel shafts 89. Said shafts each have a ratchet wheel 90 secured thereon, which are rotated alternately by pawls 91. Said pawls are oscillatably mounted on the oscillatably mounted 25 pawl bar 92, which latter is link connected with the upper end portion of rocker arm 83, for thereby oscillating said pawl bar. Pawls 91 are pivotally mounted on the manually operated and slidably mounted shifter 30 bar 93, which has studs 93' secured thereon, said studs being adapted to engage the shank ends 91' of said pawls for alternately overcoming their pawl springs 91'' and moving the hooked ends of said pawls from engagement 35 with their respective ratchet wheels 90. Said shifter bar has the two notches 93'' (see Fig. 2) formed in one edge thereof, which are alternately engaged by the free end of spring 93^a, for detachably holding 40 said shifter bar in two positions; alternately. The previously described parts form ribbon feeding means. The outer end portions of ribbon guide 86, have arms 86'' formed therewith. One of the oscillatably mounted 45 levers 94, has its inner end situated beneath said arm while its outer end projects beneath arm 103'' (see Fig. 4) which is secured on the clearing key stem 103'. The total shifting key 95 is provided with ribbon guide 50 lifting means which is like the mechanism previously described and is therefore neither designated nor described. Lifting ribbon guide 86 and the thereby guided ribbon, lift the half 86^c of ribbon 86^a into printing position, when either one of said keys is depressed. Total shifting key 95 is provided with stem 95' (see Fig. 12) the lower end portion of which has the upper end of shifter rod 95'' connected therewith, as seen 55 in Fig. 12, the lower end of said shifter rod is crank connected with the upper end of the oscillatably mounted L crank 3^a, the lower end of said crank being crank connected with the upper end of the undesignated one of shifter arms 3'', the upper ends 70 of which arms are slidably mounted on wheel shaft 1. The lower ends of said arms are secured on shifter shaft 3', (see Fig. 10) which shaft is slidably mounted in frame sides 2. The previously described sleeves 3 75 form one continuous set of sleeves between the upper ends of said shifter arms. The described shifting mechanism shifts sleeves 3 and the therewith connected parts, including cone 6, from the position seen in Fig. 10 80 to the position seen in Fig. 12, upon manual depression of key 95, and vice versa, by spring 95^a, when said key is released. The lower end of key stem 95' is crank connected 85 with the upper portion of crank 96', (see Fig. 12) which is oscillatably mounted on shaft 96. Said crank has arm 96'' formed therewith, which arm projects over the free end portion of one of the plurality of dogs 104. The other ends of said dogs are secured 90 on shaft 96, which shaft is oscillatably mounted in frame sides 2. The free ends of the central ones of said dogs are moved from the position seen in Figs. 1 and 10, to the 95 position seen in Fig. 12, with their free extremities extending into notches 18 for holding the total wheels 5 against rotation while a total is being printed, as hereinafter described. Said dogs are lifted by spring 104', seen in Fig. 11, after key 95 is released. The lower portion of crank 96' is rod connected 100 with one end of the oscillatably mounted rocking lever 97 by rod 98, seen in Figs. 1, 11 and 14. The other end of said rocking lever is provided with stud 97' which lifts the free end of arm 99, which arm is secured 105 on the oscillatably mounted rock shaft 100. Said rock shaft has arms 101 secured thereon, in the free ends of which the depressing rod 102 is secured. Said rod is situated 110 across the upper surfaces of the depressing shafts 42, for simultaneously depressing all of said shafts. The depression of said shafts depresses all of the stop bars 30 and cipher bars 43, (see Fig. 14) thereby 115 clearing said bars from their engagement with shoulders 21 and 22 respectively, (see Fig. 1) when key 95 is depressed. The previously described parts and their operations form the totaling mechanism, whereby 120 all of the involved parts of the machine are placed in proper position for printing a total as hereinafter described, including the last described parts, which form bar clearing mechanism. Referring to Figs. 1, 12 and 14, 125 key 103 is provided with stem 103', the lower end of which is crank connected with the upper portion of crank 105. Said crank is loosely mounted on shaft 96, and has arm 105' formed therewith. Said arm extends 130

over the free end portion of the adjacent stop dog 104 for lowering the free extremities of the central ones of said dogs from the position seen in Figs. 1 and 10 to 5 a position in the path of travel of lug 16 (seen best in Fig. 11) but not sufficiently low to engage the notches 18. The lower portion of crank 105 is rod connected by rod 103', with crank 106. Said crank is secured on 10 rock shaft 107, on which latter the crank 108 is secured. Said crank is moved against the free end of arm 109, which arm is secured on shaft 100, for oscillating said shaft counter clock wise and doing the same, independent 15 of the previously described totaling mechanism. This oscillation of shaft 100, moves its previously described bar clearing parts, for automatically clearing bars 30 and 43, as previously described. Rock shaft 100 is 20 oscillated clock wise by the crank connected spring 110 (see Fig. 1) for recovering its previously described movement. Shaft 107 has arms 111 (see Figs. 1 and 14) secured thereon, the free ends of which are adapted 25 to be moved downward against the free end portions of their respective latches 65, overcoming spring 64, and unlatching the latch ends of the carrying segments 62, when the total clearing key 103 is depressed, as here- 30 inafter described. For brevity, hereafter, these described parts will be termed carrying segment clearing means.

Referring to Figs. 1 and 2, the slidably mounted stop bar 112, is adapted to be slid 35 behind operating lever 52, for preventing movement, by inertia, of said lever, thereby preventing operation of the hereinbefore described key clearing mechanism, in performing examples in multiplication. This bar 40 will hereinafter be termed, lever stopping means.

In the operation of my invention, with the parts in the position seen in Fig. 1, the operator (without setting any of the keys) 45 pulls handle 52' toward the left, which by the described parts, overcomes recover springs 58, and by pull spring 57 pulls unit rack 19 toward the right, until said rack is stopped by contact of shoulder 22 with 50 cipher bar 43, as seen in Fig. 5.

This movement of said rack rotates drive gear 10 and the therewith connected lift gear 9, seen in Fig. 10. This movement lifts units type bar 67 and the thereby carried type carrier 72, which latter carries the upper one of type 71 into printing position. This movement of said type bar lifts stud 70 from pull-piece holder 76, which latter is oscillated by its weight 76' from the position seen in Fig. 1, to the position seen in 60 Fig. 6, thereby releasing stop stud 75' and its connected pull-piece 75. At this juncture, spring 77 oscillates said pull-piece from the position seen in Fig. 1, to the position seen 65 in Fig. 6, with the lower corner of said

pull-piece moved into the path of travel of the pull-piece actuating bar 79. Continued movement of handle 52' moves arm 54 against lug 81', thereby moving the parts from the position seen in Fig. 1, to the 70 position seen in Fig. 17, and rotates the bar 79 from the position seen in Figs. 1 and 6, to the position seen in Fig. 7, with its upper edge out of the path of travel of the lower corner of pull-piece 75. The thus liberated 75 pull-piece is quickly moved toward the left, by spring 77, thereby oscillating hammer bar 74'' from the position indicated by dotted lines in Fig. 1, to the position shown. The upper end of said hammer bar is 80 stopped against stop 80, upon which the inertia of hammer 74 overcomes spring 74' and moves said hammer from the position seen in Fig. 1, striking the face of said hammer against the left end of the upper one 85 of type 71. This action drives a portion of the upper half 86^b of ribbon 86^a against paper 84, thereby printing unit cipher only on said paper in the normal color. While the previously described printing operation 90 is taking place, all of the other racks 19 are held from movement by their holding bars 30. The thus printed cipher indicates that the key board is clear and that items 95 may be printed in the normal color. The desired items are now printed in the normal color, in the following manner. Any 100 desired digit key or keys 1'' to 9'' (see Figs. 1 and 2) are manually depressed, until their respective studs 38 rest upon their respective rack extensions 25, upon which springs 39 pull their respective key stem ratchets 36 beneath key board 35, thereby holding said keys in their lowered position with their studs 38 in the path of travel of shoulders 105 23 or 24, as the case may be. It will be seen in Figs. 13 and 14, that the depression of any one of said digit keys depresses its respective depressing shaft 42, thereby depressing its stop bar 30. The overlap flange 110 33 depresses the next stop bar of lower denomination, by pressure of its overlap flange 33 on the adjacent underlap flange 34, as seen in Fig. 13. For example, when a digit key of higher denomination is depressed, its own and all stop bars of lower 115 denomination are thereby depressed leaving the parts in position for printing the correlated type and ciphers of lower denomination. The previously described manual 120 movement of handle 52' toward the left is repeated, thereby repeating the previously described printing operations, which print the item on paper 84. Handle 52' is released after which by its connected parts 125 said handle is quickly returned from its described position to the position seen in Fig. 1. The inertia of said handle carries it and its connected parts including arm 49, further toward the right, thereby compressing 130

spring 48, which moves rod 45 toward the right. This movement of said rod moves the crank connected clearing shaft 44 toward the right, which similarly moves 5 the clearing bars 47. Said clearing bars move the upper ends of digit key stems 1' to 9' toward the right, thereby moving the set ratchet 36 from beneath the key board 35. At this juncture springs 39 draw the thus 10 released key stems upward thereby performing what I shall term the key clearing movement, after which the previously described digit key setting and the printing movements are repeated. The total amount of 15 said printed items is set and visibly indicated in the machine at the point which is one-half of a step below the designated total indication 14', as seen in Fig. 11. Total wheel 5 carrying said total indication is 20 rotated counter clock wise by the pawl 12 which pawl is similarly carried by drive wheel 7. When pawl 12 moves wheel 5 from the half step blank position shown in Fig. 11 to the position shown in Fig. 6, the 25 type carrying bar 67 is moved to proper position for printing a cipher as hereinbefore described, and the cipher printing operations are performed.

Upon the return movement of rack 19, 30 drive wheel 7 is thereby rotated clock wise. This movement lowers bar 67 from the position shown in Fig. 6 to the position shown in Fig. 1. This movement of wheel 7 carries pawl 12 clock-wise one-half of a 35 step to the right of the position shown, as indicated by dotted lines in Fig. 6. Repeated half step movements of the driving mechanism thereafter move pawl 12 idly from its indicated half step position to the 40 position seen in Fig. 6. This idle movement of said pawl does not rotate wheel 5 and the thereon carried total indication 14' from the visible position shown in Fig. 6. It will be seen in Fig. 1 and understood, 45 that shoulder 23, on rack extension 25, is the distance of one and one-half steps of movement from alinement with stud 38 and that the lowering of any one of the first group of studs 38 will stop shoulder 23 at a 50 point which is one-half of a step more than the number of the key stem by which said stud is lowered. The same is true in regard to the relation of shoulder 24 with the second group of studs 38. This added half 55 step of movement when transmitted by rack 19 to pawl 12 through their connected parts move said pawl through its previously described half step of idle movement and through such number of whole steps of 60 movement as the lowered key stem may determine. Continued counter clock wise rotation of wheel 5 and the thereby carried cam 5' similarly rotates cam face 5'' from the position seen in Fig. 6 to the position 65 seen in Fig. 7. Face 5'' moves and de-

tachably holds gear segment 62 from the position seen in Fig. 6 to the intermediate position seen in Fig. 7. This action takes place when the total indication, nine, has reached the designated point 14' as seen in Fig. 7. While segment 62 is thus held its flanges 62' and 62'' are in such position that upward movement of said flanges from the position shown carries said flanges clear of, and past the like flanges while in the position seen in Fig. 6. While in their described intermediate position said flanges project into the path of travel of the hereinafter described segment flanges. Upon farther counter clock wise rotation of cam 5', cam face 5'' moves and detachably holds segment 62 from the position seen in Fig. 7 to the outer position seen in Fig. 8. Referring to Fig. 1, the return movement of rack 19 carries stud 28 toward the left into engagement with shoulder 29' formed on drive gear segment 29 thereby oscillating said segment clock wise. This drives segment 62 upward from the position seen in Fig. 8 to the position indicated by dotted lines seen in Fig. 7. After segment 62 is moved to either its intermediate position seen in Fig. 7 or its outer position seen in Fig. 8, said segment is latched by engagement of its stud 63 with one of the shoulders 65' formed on latch 65, which latter is moved into said engagement by action of spring 64. Said latch is provided with the L shaped lock 63', the central portion of which is oscillatably mounted on arm 4'. The lower portion of said lock has the inclined face 63'' formed thereon, which is moved by the hereinafter described movement of stud 63''. As segment 62 approaches the limit of its upward movement indicated in Fig. 7, the right extended portion of latch 65 is thereby moved from the position shown against bar 68. Continued movement of said segment to the limit of its upward movement moves arm 4' by its connected parts, until said latch is thereby oscillated from the position shown to the position indicated by dotted lines. At this juncture the shoulder on the free end of latch lock 63' gravitates into engagement with the upper end of latch 65 for detachably holding said latch against the action of spring 64. Said spring draws the shank end of segment 62 downward until stud 63 has passed shoulder 65'. At this juncture stud 63'' is carried by said shank into contact with the slope face 63'' which, during the latter part of said movement, moves said lock from its described locked position to the position seen in Fig. 6, thereby releasing the said latch, which is drawn by spring 64 from the position indicated by dotted lines in Fig. 7 to the position seen in Fig. 6. Segment 62 is thereby oscillated from the position seen in Fig. 8 to its inner 130

position seen in Fig. 6. When segment 62 is lifted, as previously described, from the position seen in Fig. 8, its underlap flange 62' (see Fig. 9) lifts all of such 5 segments of higher denomination as may have been moved to the position seen in Fig. 7. When any segment 62 is thus moved it oscillates its arm 4'' and the therewith formed pawl arm 4 which carries pawl 66 from the position seen in Fig. 7 to the 10 position indicated by dotted lines. This movement of said pawl rotates total wheel 5 and the therewith connected parts, including total indications 14', counter clock wise one step. This movement performs the 15 operation that is usually called "carrying tens." After the tens are thus carried and the previously described movements of segment 62 have taken place said segment and 20 the therewith connected parts gravitates from the position indicated by dotted lines in Fig. 7 to the position shown in Fig. 6.

The total of the previously described printed items is printed on paper 14 in the 25 following manner: the operator depresses total key 95 which by its previously described parts slides the total wheels from the position seen in Figs. 9 and 10 to the position seen in Fig. 12, with studs 15 thereby 30 carried into the path of travel of arms 8. While the holding key 95 is in this position the central ones of dogs 104 are held in the position seen in Fig. 12 with their free extremities in the ones of notches 18 that 35 are in alinement therewith, whether said notches be the ones that are adjacent to projection 16. While key 95 is held in this position, the free extremities of the central ones of dogs 104 are held in the 40 notches 18 in the total wheels which have been rotated, and in the half step notches 18' of such wheels as have not been rotated, as seen in Fig. 11. Said dogs hold said wheels and their respective studs 15 against 45 rotation. When key 95 is thus depressed, the bars 30 and 43 are depressed by action of the previously described bar clearing mechanism, for permitting free movement of racks 19, seen also in Fig. 1. While the total 50 wheels 5 are thus held and said bars are thus cleared, said operator grasps handle 52' and moves the same toward the left. By the previously described parts, drive wheels 7 are thereby rotated until their respective 55 arms 8 are stopped by studs 15, which movement raises bars 67 and the thereby carried type 71. Said parts are thus stopped in proper position for printing said total upon paper 84, by the previously described printing operations, after which key 93 is released. 60 At this juncture the described actions of springs 95^a and 104' return their involved parts from the position seen in Fig. 12, to the position seen in Fig. 10. After the previously 65 described return movements of the

involved parts, spring 110 (see Fig. 1) oscillates shaft 100 clock-wise, which by its described connected parts releases bars 30 and 43, which are moved from their depressed position to the position seen in Fig. 1, by 70 their respective springs 30'' and 43''. After said totaling operations are completed as described, items may again be printed, after which a grand total of the entire amount of items can be printed by the previously described totaling operations. 75

The total wheels which have their half step notches 18' in register with dogs 104 are held by said dogs in their half step, blank position, against rotation, in the position seen in Fig. 11 with their respective arms 8 against said studs, which in turn hold wheels 7 and the therewith involved parts against movement. This non-movement of parts applies to total wheels of the higher denominations, which have not been rotated, and in correlation with which no printing is done on paper 84.

The total wheels 5, together with the other parts of the machine, are cleared in the following manner. Total key 103 (see Figs. 1 and 11, is manually depressed, which by its previously described connected parts, lowers the central ones of dogs 4 into the path of travel but not deep enough to enter any of the notches 18 or the half step notch 18', for stopping all of said wheels in their half step position, seen in Fig. 11. The previously described ribbon lifting means is also operated by the depression of key 103, thereby lifting ribbon 86^a, thus moving the colored portion 86^c (see Fig. 4) of said ribbon into printing position. This movement of said key, by its previously described latch unlocking parts, depresses the free end of levers 111, (see Figs. 1 and 14) which latter depress the shank portions of latch 65, thereby overcoming spring 64 and oscillating said latch from the position seen in Fig. 8, to the position seen in Fig. 6, thereby releasing gear segments 62. The operator then grasps handle 52' and moves the same from the position seen in Fig. 1, toward the left, thereby rotating the drive wheels 7, and their respective pawl connected total wheels 5, which latter are stopped in half step, blank position, seen in Fig. 11, by contact of their respective projections 16 with dogs 104. Continued movement of said handle oscillates arm 54^a from the position indicated by dotted lines in Fig. 17 to a position in alinement with the position of arm 54, (to the limit of its movement), during which the previously described parts drive hammers 74 in the same manner as for printing type 71, (see Figs. 1 and 17) except that the free ends of said hammers pass between the left ends of said type. Since the same at this juncture are being held at half step, no printing of said type upon paper 84 takes place. Said op- 125 130

erator releases handle 52' and prints the clear indication upon said paper by holding key 103 in its depressed position and again moving handle 52', as previously described.

5 This operation prints unit cipher in the ribbon color 86° on paper 84, thus showing that the machine is clear.

Multiplying is performed in the following manner: the multiplicand is set by de-

10 pressing the desired digit keys and their respective key stems one prime (1') to nine prime (9'), after which stop bar 112 (see Figs. 1 and 2) is slid toward the right until its right extremity is behind the upper end

15 portion of the actuating lever 52, which stops said lever in the position shown in Fig. 1. This prevents farther movement of said lever toward the right by action of its inertia, and prevents the action of the pre-

20 viously described key clearing mechanism. Lever 52 is thereafter drawn toward the left and released one less than as many times as there are units in the right hand figure of the multiplier. At this juncture

25 bar 112 is slid from its described position to the position shown in Fig. 2, after which handle 52' is once more moved toward the left and released, which, by the previously described operations, prints said multipli-

30 cand upon paper 84 the number of times that there are units in the right hand figure of the multiplier, and releases said digit keys. Said operator then sets said multipli-

35 cands, using the digit keys of the next higher denomination, and repeats the de-

40 scribed printing operation as many times as there are units in the next figure of the multiplier, and so on, until all of the figures of the multiplier are used. He then

45 performs the previously described totaling operations, which print the result upon paper 84.

Having fully described my invention, what I claim as new and desire to secure by

45 Letters Patent, is:

1. In a calculating machine, a rigidly mounted wheel shaft; a total wheel; a sleeve formed with said total wheel, said sleeve being rotatably mounted on said shaft; a 50 drive wheel rotatably mounted on said sleeve; engaging means whereby said drive wheel is engaged with said total wheel for rotating the latter in one direction; dis- 55 engaging means formed on said sleeve whereby said engagement is disengaged by sliding of said sleeve; and sliding means whereby said sleeve is slid on said wheel shaft.

2. In a calculating machine, a rigidly 60 mounted wheel shaft; a total wheel; a sleeve formed with said total wheel, said sleeve being slidably and rotatably mounted on said shaft; a drive wheel rotatably mounted on said sleeve; rotating means whereby said 65 drive wheel is rotated; a type bar; a plu-

rality of type carried by said bar; bar moving means on said drive wheel whereby said bar is moved longitudinally when said wheel is rotated; holding means whereby said drive wheel is held against lateral movement; 70 engaging means whereby said drive wheel is engaged with said total wheel for rotating the latter in one direction; means for sliding said sleeve on the shaft, and means for releasing the total wheel from the 75 drive wheel upon the sliding of said sleeve.

3. In a calculating machine, a rigidly mounted wheel shaft; a total wheel; a sleeve formed with said wheel; a drive wheel rotatably mounted on said sleeve; engaging 80 means whereby said drive wheel is engaged with said total wheel for rotating the latter in one direction; sliding means whereby said sleeve and the therewith formed total wheel are slid on said shaft toward said drive 85 wheel; a disengaging cone formed on said sleeve for disengaging the engagement of said wheels when said total wheel is thus slid; limiting means on said wheels whereby rotation of said drive wheel is limited 90 when said total wheel is slid toward said drive wheel; and rotating means whereby said drive wheel is rotated.

4. In a calculating machine, a rigidly mounted wheel shaft; a total wheel; a sleeve 95 formed with the central portion of said wheel the outer end portion of said sleeve projecting beyond the face of said total wheel; a disengaging cone formed on the inner end portion of said sleeve; a stop stud 100 formed on said face of said total wheel; a drive wheel rotatably mounted on the outer end portion of said sleeve; an arm formed with said drive wheel; rotating means whereby said drive wheel is rotated; pawl 105 and ratchet rotating means whereby said total wheel is rotated in one direction by similar rotation of said drive wheel; drive wheel holding means whereby said drive wheel is held against lateral movement; a 110 key operated slidably mounted shifter whereby said sleeve and the therewith formed total wheel are slid toward said drive wheel, for carrying said stop stud into the path of travel of said arm and for moving said cone into disengaging position for disengaging said pawl and ratchet rotating means; total wheel holding means operated by said key for holding said total wheels 115 against rotation; and printing means controlled by the rotation of said drive wheel.

5. In a calculating machine, a rigidly mounted wheel shaft; a total wheel having a hub sleeve formed therewith said sleeve being slidably and rotatably mounted on said shaft; a drive wheel rotatably mounted on said sleeve; means for shifting said sleeve for interlocking said total and drive wheels; rotating means whereby said drive wheel is rotated; a plurality of digit keys for stop- 125 130

ping said drive wheel rotating means at various points of its movement; a type carrier provided with printing type mounted therein; carrier moving means operated by rotation of said drive wheel for moving said type one at a time, into printing position; an oscillatably mounted hand crank whereby said drive wheel rotating means is moved for rotating said drive wheel; printing means operated by said hand crank as the same approaches the limit of its manually actuated movement; and recover springs for recovering the movement of said manually operated hand crank.

6. In a calculating machine, a rigidly mounted wheel shaft; a total wheel having a hub sleeve formed therewith said sleeve being rotatably mounted on said shaft; a drum formed with said total wheel; a stop projection formed on the peripheral surface of said drum; a drive wheel; pawl and ratchet rotating means for rotating said total wheel and its connected parts in one direction by the rotation of said drive wheel 20 in the same direction; a dog; moving means

whereby said dog is moved into the path of travel of said stop projection for stopping said rotation of said total wheel and the therewith ratchet connected drive wheel; manually operated rotating means whereby 30 said drive wheel is rotated in said one direction and recover springs whereby said manually operated rotating means and the thereby rotated drive wheel are returned to normal position.

7. In a calculating machine; an oscillatably mounted operating lever; recover springs for returning normal movement of said lever; key clearing means operated by said lever for clearing set digit keys during the last portion of the normal recover movement of said lever; and a slidably mounted key control stop bar which is manually slid into the path of travel of said operating lever for stopping the latter against movement through said last portion of its normal recover movement; for preventing operation of said key clearing means.

In testimony whereof I affix my signature.
OSCAR H. HALSTEAD.
